DOUBLE SIGNAL SYSTEM

Manfred W. Muchter, Nutley, N. J., assignor to
 American District Telegraph Company, New
 York, N. Y., a corporation of New Jersey

Application July 12, 1938, Serial No. 218,795

11 Claims. (Cl. 177—367)

This invention pertains to signal systems generally and more particularly to signal systems of the type used for supervising watchman's tours or for fire alarm circuits or other circuits used in a supervisory sense. It is desirable in these particular applications that signals should be received during abnormal conditions of the signaling circuit, such as grounded transmitters, grounded line or shorted transmitters and shorted lines, and even direct short-circuits across the circuit at the central office. The system embodying this invention is similar to the well known McCulloh system wherein the circuit can be changed for the purpose of receiving the signals during the above-mentioned abnormal conditions except that the circuit contains refinements which provide for more efficient operation under McCulloh conditions and further provides for non-interfering simultaneous transmission of signals from two transmitters on the same circuit.

The primary object of this invention is to provide a signal circuit of the type mentioned above for accomplishing the results and overcoming the difficulties and abnormal conditions mentioned above.

Another object of this invention is to provide an improved signal system wherein two transmitters on the same circuit may simultaneously transmit signals without interfering with one another.

A further object of this invention is to provide a signal system wherein two transmitting stations are arranged to be non-interfering and to simultaneously transmit signals to the central station where the signals may be simultaneously recorded on either a double pen register or on two separate registers.

Another object of this invention is to provide a signal system of the McCulloh type wherein two signal boxes on the same transmission line may simultaneously transmit signals over different sides of the same line circuit.

A still further object of this invention is to provide for non-interfering simultaneous transmission of two box signals on the same circuit and to further provide a differential relay for controlling the central office circuit under both normal and abnormal conditions of the circuit.

A further object of the invention is to provide a double-signal McCulloh system which includes means for accomplishing non-interfering simultaneous transmission of two box signals over the same circuit and automatic means for changing

the central office circuit to provide McCulloh operation.

This system is of the double-signal McCulloh type which provides for non-interfering simultaneous transmission of signals from at least two boxes on the same circuit. The system also includes two recorders or a double pen register for each circuit. If only one box or transmitter is operated, the signal will be recorded by both registers or both pens of a double pen register whereas if two transmitters are operated at the same time, one pen will record one signal and the other pen will record the second signal. If more than two transmitters are operated simultaneously the two transmitters located nearest to the two ends of the circuit will operate the recorders while the other transmitters will be prevented from interfering. Unless the signals completely overlap, part of the signals will be received before or after the transmission of the signals by the transmitters located nearest to the ends of the line. The transmitters are of the conventional type and are arranged so that ground is not ordinarily connected to the code wheel but a cam contact applies the ground to the pen springs during the transmission of the first break impulse and thereafter the circuit is either open or grounded during the transmission of a signal. At the end of the signal the ground connection is automatically removed.

The McCulloh circuit itself is somewhat different from the standard circuit in that the ground relay is of the differential type and is normally in a deenergized condition. The purpose of the differential relay is to provide more efficient operation during abnormal conditions of the line circuit such as grounded transmitters, grounded transmission line or short-circuits in the circuit, even short-circuits across the line itself.

The foregoing and more specific objects will appear from the following complete disclosure of the invention.

The drawing shows a circuit diagram of a system embodying the invention.

In general, the drawing shows a line circuit including a plurality of transmitters I, II and III arranged in series relation, a line relay 15 and a differential relay or ground relay 10, both arranged in series relation to the transmission line. The line relay 15 and the ground relay 10 control relays 25, 30, 40 and 70 which in turn control the registers 50 and 60. Battery 20 is common to the whole circuit but is shown connected at different points in the circuit in order to avoid complication of the drawing,

For the normal line condition, the supervisory circuit can be traced from battery 20 through the right hand winding of relay 10, a line compensating resistor 6, the "out" jack, the line circuit including the boxes I, II and III, the "in" jack, the right hand winding 11 of line relay 15, break contact 43 of main switching relay 40 and the left hand winding 11 of relay 10 to ground. Since the windings 11 and 12 of the relay 10 are equal and opposing, this relay is normally deenergized and relay 15 is normally energized by the supervisory current. The impulse limiting relay 25 is normally energized from battery 20 through back contact 13 of relay 10.

When a box or transmitter is operated, a break impulse is transmitted due to the opening of the line circuit by the spring 2 for instance, which is operated by the code wheel thereby causing the line relay 15 to release. This closes a circuit from battery 20 through back contact 13 of ground relay 10, back contact 40', back contact 18 of line relay 15, back contact 73 of auxiliary switching relay 70, back contact 45 of main switching relay 40 to the winding of impulse limiting relay 30 and ground, thereby operating slow release relay 30. Ground relay 10 is not affected by the break impulse since both windings are deenergized when the code wheel opens the line circuit. During the transmission of the first break impulse, the pen spring 1 closes to prepare the circuit for the ground signal. Ground relay 10 is energized when the code contacts close, from battery 20 through winding 12, the winding 11 being shunted by ground. The armature of ground relay 10 closes the make contact to energize the main switching relay 40 through the left-hand normally closed switch contact of switch 39 and winding 41 to ground. Another circuit can be traced from battery 20 through the make contact 13' of ground relay 10 through conductor 14, through contact 34 of impulse limiting relay 30, through conductor 35, contact 27 of impulse limiting relay 25, series resistor 49 and register 60 to ground, thereby causing the first impulse to be recorded. As impulse limiting relays 25 and 30 are of the slow release type, their armatures remain operated for a certain length of time, even though the circuit is opened at the back contact of ground relay 10. Switching relay 40 operates to disconnect the line relay 15 from the left hand winding 11 of ground relay 10 and connect it through a compensating resistance 7 to battery 20 and ground by means of contact 43'. Since at this time ground is connected to the line by the transmitter, line relay 15 operates and energizes the other register 60 through a circuit which can be traced from battery 20 through make contact 44, contact 18' of relay 15, contact 33 of relay 30, make contact 48 of relay 40, compensating resistance 59 through the register 60 to ground. In order to speed up the response of line relay 15 to the ground impulse, this relay is provided with a second winding 16 which is energized in multiple with the circuit of the ground register 60 through contact 46 of relay 40 until main switching relay 40 picks up. At that time a circuit is also closed for auxiliary switching relay 70 which can be traced from battery 20 through contacts 44 and 44' of relay 40, contact 32 of relay 30 and winding 71 of relay 70 to ground. Auxiliary switching relay 70 picks up and closes a locking circuit through its right hand contact 74 and make contact 31 of relay 30 to battery, and contacts 74 also bridge contact 32, thereby preventing auxiliary switch-

ing relay 70 from releasing until both relays 30 and 40 are deenergized. The following break impulse causes relays 10 and 15 to deenergize resulting in a space on the recorder tape. The circuit of relay 40 is interrupted at this time but since it is of the slow release type it will not release its armature during the transmission of break impulses. At the time of the transmission of break impulses, relays 25 and 30 are again energized. After the first break impulse, however, the circuit for relay 30 is changed due to the operation of relays 40 and 70 causing it to be energized in a circuit which can be traced from plus through make contact 44 of relay 40, break contact 18 of relay 14, make contact 73' of relay 70 through the relay 30 to ground. Relays 10 and 15 are energized after each break impulse of the transmitter causing the two register circuits to be energized and to record impulses on the tape. At the end of a digit, the register circuits would be energized for the whole time of the interval until the first break impulse of the succeeding digit, but for the action of impulse limiting relays 25 and 30 which release after a short delay, cutting or limiting the recording impulse to its normal length, this also being true for the ground condition following the transmission of the last break impulse of the signal.

The ground contact 1 of the transmitter stays closed as long as the transmitter is running. When the transmitter finally removes the ground connection from the line, relays 10 and 15 drop out and stay deenergized, causing main switching relay 40 to release after a certain time. This relay restores its contacts to the normal condition, relay 15 picks up again through the normal line circuit opening the circuit of impulse limiting relay 30 at break contact 18 (relay 30 had been energized at the time line relay 15 released upon removal of the ground from the line circuit). The closure of make contact 18 however does not cause another impulse to be recorded on register 60 since make contact 48 and contact 75 are both open. When impulse limiting relay 30 releases after a short interval of time, armature 31 drops and as contact 44' is already open, relay 70 is released. Contact 75 closes but contact 33 being open the register circuit of register 60 is still open. Everything is now in normal condition again.

If two or more transmitters are operated simultaneously, the circuit will function in substantially the same manner as described above. However, the two transmitters located nearest to the ends of the line will transmit their signals to the register magnets respectively without interfering with one another and without being interfered with by additional boxes between them that may be operating at the same time since the line beyond the box nearest to either side of the circuit will always be either open or grounded. Consequently, whatever signal is put on the line beyond this box will have no effect. When two transmitters operate simultaneously one will operate the ground relay 10 which controls the register 60 through a circuit from battery 20, contact 13, line 14, contact 34 or 76, line 35, contact 27, resistor 49 to register 60. The transmitter at the other end of the line will control register 60 through a circuit which can be traced from battery 20, contact 44, make contact 40', make contact 18' of line relay 15, contact 33, make contact 48, resistor 59 to recorder 60 and ground, as explained above.

If two signals are being transmitted, one of

them may be broken up if a third transmitter nearer to the office on the line circuit is started. However, this third signal will be transmitted without interference.

It may appear that since the circuit is thrown to the McCulloch condition during the transmission of a signal, that ground at the box is essential for the transmission of a signal. However, this is only true so far as the non-interference feature is concerned. If the ground connection of a transmitter becomes defective for some reason, the operation of the circuit will be slightly different. During the transmission of the first break impulse by the code wheel 2, impulse limiting relay 30 will again be energized as explained above. At the termination of the break impulse the line circuit is closed again and line relay 15 picks up to record the impulse on the associated register 60 through a circuit which can be traced from battery 20 through contact 13, back contact 40', make contacts 18', and 33, back contacts 17 and 75, series resistor 59 and register 60 to ground. As ground relay 10 is not operated at this time, switching relays 40 and 70 likewise fail to operate. The line circuit remains in a normal condition and the signal is only recorded on the side of the register associated with line relay 15. This is an indication to the operator of a trouble condition at the particular transmitter. This trouble condition may also be a shunt across the box as will be explained below. Even if the ground connection to a transmitter should become faulty during the transmission of a normal signal, the circuit will be automatically conditioned to properly receive the remainder of the signal. It will be recalled that during the transmission of a normal signal, the line circuit is thrown into the McCulloch condition and signals are transmitted through ground. In case this ground connection should become faulty during the operation of the transmitter, relays 10 and 15 will drop out immediately and stay deenergized, but after a short interval of time, switching relay 40 releases, restoring the line circuit to the normal condition and permitting the line relay 15 to follow the break impulses and to record the signal on the tape as soon as relay 10 is deenergized. This occurs upon the release of relay 30 during the first longer space between break impulses or even on the first space, if the box is fairly slow.

In case the transmitter contacts become short-circuited, or if the entire loop becomes short-circuited for some reason, a signal can still be sent from the particular transmitter or transmitters involved. In this case no break impulse is transmitted when the pen contacts of the box open the first time. However, since the ground connection is established at this time, ground relay 10 picks up when the transmitter springs 2 reclose and energizes relay winding 41 of main switching relay 40 through conductor 14 and the left hand normally closed contact of the switch 39. Line relay 15 is momentarily shunted by ground at the transmitter and fails to close a circuit through its back contact as its local winding 16 is energized as soon as relay 10 closes its make contact through a circuit from battery 20, make contact 13', conductor 14, contact 46 and winding 16 to ground. When the make contact 43' has closed due to energization of winding 41, line relay 15 is energized through its line winding 17 during the remainder of the ground impulses. The ground register will not receive any impulses since contacts 34 and 76 are open. However, the

register 60 is energized by a circuit which can be traced from battery 20 through make contacts 44, 18', 47, 26, and contact 75 to register 60 and ground, recording an impulse on the tape.

- 5 Auxiliary switching relay 70 fails to pick up since line relay 15 failed to release and energize impulse limiting relay 30 leaving contact 32 open. In this case relay 25 acts as the impulse limiting relay for register 60 by means of its contact 26.
- 10 When, during the following break impulse, relays 10 and 15 are deenergized, relay 30 again fails to operate since its circuit is open at the break contact 45'. The following ground impulse is again recorded on the register associated with the armature of line relay 15 as described above. As in the case of a signal from a transmitter with a faulty ground connection, the signal is again recorded on only one side of the register thus giving an indication of a trouble condition 15 and in this particular case a shunt condition on the line.

In case of a leakage condition on the line that is not of sufficient intensity to give an indication by operating the differential ground relay 10, all 20 transmitters will still be able to transmit a signal providing that there is a leakage on only one side of the transmitter. Line relay 15 will respond to the first break impulse and energize impulse limiting relay 30 through a circuit which can be traced from battery 20 through back contacts 13, 40', 18, 73, and 45 and relay 30 to ground. Ground relay 10 will also operate as soon as the following ground impulse is transmitted and cause main switching relay 40 to operate. This relay, as previously, throws the circuit to the McCulloch condition and also causes auxiliary switching relay 70 to pick up. If the transmitter is located between the leakage and the relay 15, relay 10 may then remain energized 25 through the leakage, independently of the transmitter, and the signal will be recorded by the line relay 15 following the code.

If the box is located between sufficient leakage and the ground relay 10, the line relay 15 will not follow the condition but will hold up through 30 the leakage after the first ground impulse has been made. The ground relay 10, however, will follow the code.

In case relay 10 or 15, or both, remain energized through the leakage at the end of the signal, main switching relay 40 will also remain energized. Relay 40 is provided with a locking winding 42 for holding this relay energized in case line relay 15 should remain energized at the end of the signal, but not ground relay 10. This locking circuit can be traced from battery 20 through make contacts 44, 18' and 47 and winding 42 to ground. An indication of trouble is obtained by the lighting of the trouble lamp 51 which is energized from battery through make contacts 44, 44', back contact 31' or from battery through make contact 31, then through resistance 52, lamp 51, through right-hand normally closed contact of the switch 39 through the common trouble relay 55 to ground, thereby advising the operator of the trouble condition.

In case of a ground sufficient to operate the ground relay 10, an indication is given through the trouble lamp circuit as traced above, through make contacts 44, 44' and back contact 31'. The operator throws the McCulloch conditioning switch 39, which takes the trouble lamp circuit off the trouble relay and connects it directly to ground as shown in the drawing. The other blade of the switch connects winding 41 of main

switching relay 40 in series with winding 72 of auxiliary switching relay 70, thereby energizing both relays 40 and 70; relay 40 throws the line circuit to the McCulloh condition. The same is true in case of a break, except that the trouble lamp circuit in this case is closed through make contact 31, relay 30 picking up when the armature of relay 15 releases to close the break contact. In either case, signals on either side of the trouble can still be transmitted, since either of the relays 10 or 15 will follow the impulses and operate the corresponding register.

It will be apparent from the foregoing description that I have devised a novel non-interfering, simultaneous double signal McCulloh system.

The present invention is susceptible of various modifications within the scope of the appended claims which will be obvious to those skilled in the art.

I claim:

1. In a signalling system, a transmission line, a plurality of stations connected in said line, a relay responsive to ground impulses connected to one end of said line, another relay responsive to breaks in said line and connected to the other end of said line, a switching relay energized by contacts of said first relay for energizing said second relay through ground whereby said second relay responds to ground signals, a recorder and switching means controlled by said main switching means for connecting said recorder to contacts of said second relay whereby the ground signals are recorded during short-circuits of said line or said stations.

2. In a signal system, a transmission line, a plurality of transmitting stations connected in series in said transmission line for transmitting break and ground signals, a grounded source of potential, a differential relay connected in series with said line, one coil of which is connected between one end of said line and said source whereby it is energized by ground signals to operate the relay, the second coil of which is connected to the other end of said line and ground whereby it may be shunted by ground at the stations, said coils normally being energized to balance one another whereby line leakage does not cause false signals, a line relay connected in series in said transmission line and with the second coil of said differential relay whereby the line relay is responsive to break signals, a slow to release main switching relay operated by said differential relay for disconnecting the second coil of the differential relay and connecting said line relay coil to battery whereby it is energized by ground signals, a slow to release auxiliary switching relay energized by said line relay in response to the first break signal, a recorder connected by said switching relays to contacts of said line relay for recording signals from one side of the line and another recorder connected to contacts of said differential relay by said auxiliary switching relay for recording signals from the other side of the line whereby signals from two separate transmitters may be received and recorded simultaneously.

3. In a signal system, a transmission line, a plurality of transmitting stations connected in series in said transmission line for transmitting break and ground signals, a grounded source of potential, a differential relay connected in series with said line, one coil of which is connected between said line and said source whereby it is energized by ground signals, the second coil of which is connected to the other end of said line

and ground, said coils normally being energized to balance one another, a line relay connected in series in said transmission line whereby the line relay is responsive to break signals, a switching relay operated by said differential relay for disconnecting the second coil of the differential relay and connecting said line relay coil to battery whereby it is energized by ground signals, a recorder controlled by the line relay for recording signals from one side of the line and another recorder controlled by the differential relay for recording signals from the other side of the line whereby signals from two separate transmitters may be received and recorded simultaneously.

4. In a signal system, a transmission line, a plurality of transmitting stations connected in said transmission line for transmitting break and ground signals, a grounded source of potential, a differential relay connected in series with said line, one coil of which is connected between one end of said line and said source whereby it is energized by ground signals, the second coil of which is connected to the other end of said line and ground, said coils normally being energized to balance one another whereby line leakage does not disable the system, a line relay connected in series in said transmission line and with the second coil of said differential relay whereby the line relay is responsive to break signals, a main switching relay operated by said differential relay for disconnecting the second coil of the differential relay and connecting said line relay coil to battery whereby it is energized by ground signals, an auxiliary switching relay energized by said line relay, a recorder connected by said switching relays to be controlled by said line relay for recording signals from one side of the line and another recorder connected by the auxiliary relay to be controlled by said differential relay for recording signals from the other side of the line whereby signals from the two separate transmitters may be received and recorded simultaneously.

5. In a signal system, a transmission line, a plurality of transmitting stations connected in series in said transmission line for transmitting break and ground signals, a grounded source of potential and a differential relay connected in series with said line, one coil of which is connected between one end of said line and said source whereby it is energized by ground signals, the second coil of which is connected to the other end of said line and ground, said coils normally being energized to balance one another but becoming unbalanced during certain leakage conditions whereby break signals may be repeated by said relay.

6. In a signal system, a transmission line, a plurality of transmitting stations connected in series in said transmission line for transmitting break and ground signals, a grounded source of potential, a differential signal repeating relay connected in series with said line, one coil of which is connected between one end of said line and said source to operate the relay, the second coil of which is connected to the other end of said line and ground, said coils normally being energized to balance one another and a line signal repeating relay connected in series in said transmission line and with the second coil of said differential relay.

7. In a signal system, a transmission line, a plurality of transmitting stations connected in series in said transmission line for transmitting break and ground signals, a grounded source of

potential, a differential relay connected in series with said line, one coil of which is connected between one end of said line and said source whereby it is energized by ground signals to operate the relay, the second coil of which is connected to the other end of said line and ground whereby it may be shunted by ground at the stations, said coils normally being energized to balance one another whereby line leakage does not cause false signals, a line relay connected in series in said transmission line and with the second coil of said differential relay whereby the line relay is responsive to break signals and a main switching relay operated by said differential relay for disconnecting the second coil of the differential relay and connecting said line relay coil to battery whereby it is energized by ground signals.

8. In combination, a transmission circuit comprising a transmission line, a grounded source of potential connected to one end thereof, a plurality of transmitters in said line, each of which comprises a contact for continuously grounding the line during transmission of each digit and other contacts for breaking the line in accordance with the code, a signal repeating means comprising a differential relay, one coil of which is connected between one end of said line and said source of potential whereby it can respond to ground signals originating in the portion of the line between itself and a line break or to signals from a shunted transmitter, the other coil of which is connected between the other end of said line and ground whereby it can respond to signals originating on the other side of said line, and a line relay connected in said other side of the line and responsive to normal signals therein or to line make and break signals in the absence of ground at one or more transmitters and circuit converting means comprising transfer contacts in the line between the line relay and the differential relay, one of which is normally closed to the differential relay and the other of which is normally open and connected to the grounded source of potential and a relay connected to contacts of the differential relay and operated by it for operating the transfer contacts to disconnect the differential relay from the line relay and connect the source of potential to the line relay whereby it may repeat signals from one side of the line and the differential relay may repeat signals from the other side of the line.

9. In combination, a transmission circuit comprising a transmission line, a grounded source of potential connected to one end thereof, a plurality of transmitters in said line, each of which comprises a contact for continuously grounding the line during transmission of each digit and other contacts for breaking the line in accordance with the code, a signal repeating means comprising a differential relay, one coil of which is connected between one end of said line and

said source of potential whereby it can respond to ground signals originating in the portion of the line between itself and a line break or to signals from a shunted transmitter or several of them, the other coil of which is connected between the other end of said line and ground whereby it can respond to signals originating on the other side of said line, and a line relay connected in said other side of the line and responsive to normal signals therein or to line make and break signals in the absence of ground at one or more transmitters and circuit converting means comprising a switch operated by the differential relay for disconnecting the differential relay from the line relay and connecting the source of potential to the line relay whereby the line relay may repeat signals from one side of the line and the differential relay may repeat signals from the other side of the line.

10. In combination, a transmission circuit comprising a transmission line, a grounded source of potential connected therein, a plurality of transmitters in said line, each of which continuously grounds the line during transmission of each digit and breaks the line in accordance with the code, a signal repeating means comprising one coil which is connected between one end of said line and said source of potential whereby it can respond to ground signals originating in the portion of the line between itself and a line break or to signals from a shunted transmitter, and another coil which is connected between the other end of said line and ground whereby it can respond to signals originating on the other side of said line, and a line relay connected in said other side of the line and responsive to normal signals therein or to line make and break signals in the absence of ground at one or more transmitters.

11. In combination, a transmission circuit comprising a transmission line, a grounded source of potential connected to one end thereof, a plurality of transmitters in said line, each of which comprises a contact for continuously grounding the line during transmission of each digit and other contacts for breaking the line in accordance with the code, a signal repeating means comprising a differential relay, one coil of which is connected between one end of said line and said source of potential whereby it can respond to ground signals originating in the portion of the line between itself and a line break or to signals from a shunted transmitter, the other coil of which is connected between the other end of said line and ground whereby it can respond to signals originating on the other side of said line, and a line relay connected in said other side of the line and responsive to normal signals therein or to line make and break signals in the absence of ground at one or more transmitters.

MANFRED W. MUEHTER.
